UNITED STATES PATENT OFFICE.

ABRAM WALRATH AND EDWARD L. TRAVER, OF WEEDSPORT, NEW YORK, SAID TRAVER
ASSIGNOR TO SAID WALRATH.

SILO.

No. 858,841.

Specification of Letters Patent.

Patented July 2, 1907.

Application filed April 3, 1906. Serial No. 309,652.

To all whom it may concern:

Be it known that we, ABRAM WALRATH and EDWARD L. TRAVER, citizens of the United States, and residents of Weedsport, in the county of Cayuga, in the State of New York, have invented new and useful Improvements in Silos, of which the following, taken in connection with the accompanying drawings, is a full, clear, and exact description.

This invention relates to the class of silos which are composed of vertical staves bound by hoops and provided with a vertically extended doorway.

The object of the present invention is to provide simple, inexpensive and efficient means for removably securing the doors in the doorway. And a further object of the invention is to provide a simple, convenient and reliable brace for maintaining the doorposts straight and parallel. And to that end the invention consists in the improved construction and combination of parts hereinafter described and claimed.

20 In the accompanying drawings Figure 1 is an elevation of a silo embodying our improvements. Fig. 2 is an enlarged horizontal transverse section of one of the doors and adjacent portions of the silo; Fig. 3, is a further enlarged vertical transverse section on the line 3 3 in Fig. 2; Fig. 4 is a detached perspective view of one of the silo-doors; and Fig. 5 is an enlarged detached plan view of one of the spreader-bars of the silo.

Similar letters of reference indicate corresponding parts.

30 A—denotes the body of the silo which is formed from vertical staves —a— bound together by means of hoops —b— embracing the said body in the usual manner. The body —A— is provided with a vertically extended doorway and with doorposts, c c, at opposite sides of the doorway. Said doorposts are provided or formed with beveled inwardly facing jambs —d— to which are fitted the vertical edges of the doors —D—D—.

For securing the doors in the doorway we employ on 40 one of the vertical edges of each door an outwardly projecting hook —e—, which has its end portions extending approximately at right angles in opposite directions from the central portion and is rigidly attached at one 45 of said end portions to the exterior of the door —D— and in such a position as to cause the central portion of said hook to extend directly across the door-post —c— in close proximity thereto while the outer end portion of said hook engages the outer face of the door-post as clearly shown in Fig. 2 of the drawings. The said hook 50 is capable of preventing the door from dropping out of the doorway, during the operation of shifting the door vertically in its position as hereinafter explained.

Near the opposite vertical edge of the door, we employ a suitable clamp —C— for engaging the door-post —c— thereat.

We do not limit ourselves to the specific form of clamp shown in the drawings, inasmuch as the same or similar effect may be produced by different styles of clamps. The clamp herein shown is pivoted on the outer end of a bolt —f— which passes through a post 55 —g— fastened to the door. The engaging part of said clamp is beveled and bears on the exterior of the door post —c—, which is preferably provided with a metal strip —h— on which the engaging clamp bears. By turning the clamp of the uppermost door —D— sufficiently to loosen the door thereat on the jamb —d— without allowing the clamp to completely lose its hold on the door-post, the said door can be pushed up and reclamped in its elevated position to form an opening beneath it for removing therethrough ensilage from the 60 silo when required. Each succeeding lower door can be removed as aforesaid, according to the height of the remaining ensilage.

We place the door-posts flush with the exterior of the silo to allow the hoops —b— to bear on the outer 75 faces of the door-posts and continue directly across the doorway and at the same time maintain the hoops in proper contact with the staves adjacent to the doorposts as shown in Fig. 2 of the drawings.

Our described door-fastening devices are especially well adapted for a door which is composed of a tier of transversely disposed stave-sections —j— tied together by means of dowels —k— passing vertically through said stave-sections as shown in Figs. 2 and 4 of the drawings. On a door of this construction, 80 the hook —e— and clamp —C— are attached to opposite ends of one of the stave-sections —j— which possesses the requisite stability to prevent its flexure.

To maintain the two door-posts straight and parallel, we employ spreader-bars —l— which extend across 90 the doorway and are placed near to the outer faces of the doors and in line with the direction of the pressure exerted on the door-posts by the staves —a— when the hoops are tightened on the silo. We form each of the spreader-bars —l— of a straight stout iron or steel 95 rod, the ends of which are formed with right and left wood-screws —n— which are tapered or gimlet-pointed, as shown in Fig. 5 of the drawings. The threads of said screws are coarse and deep to obtain a secure hold in the wood of the door-posts throughout the depth of penetration, and thus prevent said door-posts being twisted or turned by the pressure received from the adjacent staves.

The aforesaid improved effects are more particularly

obtained from the arrangement of the spreader-bars being in lines within the thickness of the staves adjacent to the door-posts. Aside from these improved effects we save the time and labor of boring completely 5 through the door-posts and also the expense of nut usually applied to spreader bars employed for that purpose.

What we claim as our invention is:—

1. A silo having a vertically extended doorway provided with doorposts disposed flush with the exterior of the silo, straight spreader-bars formed with right and left threaded wood screws screwed into the doorposts in lines within the thickness of the staves adjacent to said doorposts, and hoops bearing on the outer faces of the 15 doorposts and continued across the doorway as set forth and shown.
2. A silo having a vertically extended doorway, door-

posts disposed flush with the exterior of the silo and formed with inwardly beveled jambs, doors seated removably on said jambs hooks having their end portions 20 extending approximately at right angles in opposite directions from the central portions and rigidly attached at one end portion to the door and having the outer end portions bearing on the outer face of the adjacent doorpost, clamps on the doors engaging the opposite door post, 25 straight spreader-bars formed with right and left threaded wood screws screwed into the doorposts in lines within the thickness of the staves, and hoops bearing on the outer faces of the door posts and continued across the doorway substantially as set forth and shown.
